UNITED STATES PATENT OFFICE.

JOHN HEANEY, OF GRIDLEY, CALIFORNIA, ASSIGNOR OF ONE-HALF TO
A. L. CHAUDET, OF NEW YORK, N. Y.

HEMP-BRAKE.

SPECIFICATION forming part of Letters Patent No. 641,010, dated January 9, 1900.

Application filed May 24, 1898. Serial No. 681,581. (No model.)

To all whom it may concern:

Be it known that I, JOHN HEANEY, residing at Gridley, in the county of Butte and State of California, have invented certain new and useful Improvements in Hemp-Brakes, of which the following is a specification, reference being had therein to the accompanying drawings.

This invention relates to machines for braking hemp in making tow.

10 The object of the invention is to produce a machine in which the tow is delivered or doffed from the cylinder of the brake with little knotting or bunching; and the special improvement of the machine is mainly in the doffer.

15 Figure 1 is a broken side elevation of so much of the brake and doffer as is necessary to illustrate my invention. Fig. 2 is a broken top plan of the same.

20 A in the drawings indicates the frame or support of the machine, of any suitable form. Parts are omitted or broken away for convenience of illustration.

25 B indicate the usual brake-rolls of a hemp-brake, the same being driven by any suitable or usual driving-gear, as at C^b.

The cylinder C, inclosed in the casing C', is the usual cylinder or shell-roller of a hemp-brake. The cylinder is provided with the 30 usual tooth-bars D, by which, acting with the shell, the shives are beaten or removed in great measure from the broken hemp. The relation of the fluted rolls B, smooth rolls B', and cylinder C are much as usual, except that 35 cylinder C is much larger than in any usual machine. Cylinder C is driven by usual means, as pulley C².

The tow is carried by the cylinder C in the direction of the arrow, as is usual. The tendency of the cylinder is to carry the fiber directly around, thus winding up the fiber on the cylinder.

40 It has been common heretofore to use a rotary brush as a doffer, said brush rotating in rather close relation to the cylinder to brush the tow therefrom; but with a brush of this character the tow brushed from the cylinder frequently winds on the brush, and as the brush must run at a high speed the tow or 45 fiber is bunched and knotted thereby. It has also been a practice to use the upper surface

of an endless-belt conveyer to carry away the tow from such a doffer; but such a device is not sure to carry all the fiber, and the doffer-brush causes bunches of fiber on such a belt. 55 My improved doffer, which works to deliver the tow or fiber in much better condition than machines heretofore used with which I am familiar, uses as a doffer an endless apron, as E, supported on two cylinders, as F F', and 60 provided with slats G, having teeth H. The belt or apron E, preferably of canvas, is wider than the length of cylinder C, and the supporting cylinders F F' are long enough to carry this endless-belt carrier so that the 65 edges of the belt project, say, a foot at each side beyond the ends of the cylinder C. Slats G—say about a foot apart, more or less—extend across the belt E. In these slats, extending as far as the width of the cylinder C, there 70 are teeth H—say two inches long and four inches apart, more or less—and these teeth run in close proximity to the teeth on cylinder C as the belt or apron moves in the direction indicated by the arrow. The belt or apron 75 may be driven by a pulley I on roller F or in other suitable manner.

The belt E runs in such direction as to take the tow or fiber from the cylinder C and carry or draw the fiber along its under side away 80 from the cylinder. The current of air produced by the rotation of the cylinder C and the travel of apron E carries the fiber along on or near the under side of the belt E until the fiber is well away from the cylinder, 85 when the fiber falls to the floor or into any suitable receptacle. It will be seen that the surface travel of the endless belt along the line of nearest proximity to C is downward and in reverse direction to the surface travel 90 of the cylinder along the same line. Thus, while the cylinder, or the teeth thereon, tends to lift the fiber toward the doffer-belt, the belt tends to and does resist and overcome this tendency. The surface movement of the 95 doffer is more rapid than that of the cylinder, and therefore the fiber is caught and carried along by the doffer, being supported only by the air-currents produced by the machine and by the pulling action of the doffer, and 100 as these forces are overcome the fiber falls below the doffer in a condition much more

free from bunches and knots than the tow from any other machine with which I am familiar.

The extension of the belt or apron beyond the ends of the cylinder C prevents the fiber from becoming entangled in the bearings of roll F and also guides the air-currents, so that the fiber is more effectually supported against the under face of apron E than if the apron is 10 only as wide as the cylinder C, as I have ascertained by actual use.

The length of apron E should be sufficient to draw out long fiber from the cylinder C without danger of the fiber being carried upward over the end of the apron. About 15 twelve feet has been found a convenient length of belt or apron in working in long-fiber hemp, such as is raised in California.

The cylinder or roll F' need not be driven 20 at as high speed as the brush heretofore used as a doffer. This is not only a saving of power, but tends to secure less bunching or knotting of the tow. In fact, for various reasons the improved doffer delivers a better 25 quality of tow from the same grade of hemp than other machines which I know to be in common use.

What I claim is—

1. In a hemp-braking machine, the combination with a toothed brake-cylinder of usual construction, driven to lift the fibers upwardly at the side opposite the feed, of an endless apron provided with slats and teeth, and moving around one support near the 35 face of the brake-cylinder and another remote therefrom, in direction to remove the fiber downwardly from the brake-cylinder and along the lower surface of the belt without mechanical support immediately below said 40 doffer, and at a speed greater than the speed of the cylinder, and driving means for said cylinder and doffer, substantially as described.

2. In a machine of the character described, the brake-cylinder, the doffer-apron of greater width than the length of the brake-cylinder, 45 and the slats and teeth carried by said apron to comb the fiber from the cylinder and convey it against the under surface of the apron without other mechanical support and means for driving the doffer-apron at a speed exceeding the surface speed of the cylinder, substantially as described.

3. In a machine of the character described, the brake-cylinder, the endless apron running in proximity thereto and of greater width than 55 said cylinder, and the slats on said apron extending the full width of the apron but having teeth only to the extent of the width of the cylinder and means for driving the belt to move the fiber downwardly, whereby said 60 fiber is conveyed along the under surface of the belt without other mechanical support, substantially as described.

4. In a hemp-brake, the brake-rolls in pairs in proximity to the shell roller or cylinder, the 65 cylinder provided with the usual toothed bars, and driven to carry the fiber forward on the lower side of said cylinder, and the doffer, consisting of an endless apron provided with toothed slats and supported on small cylinders 70 parallel with the shell-roller, one of said cylinders being close to the shell-roller and the other remote therefrom, said belt being driven at a speed greater than the surface speed of the shell-roller and acting to comb 75 the fiber downwardly and convey it by engagement with the teeth on its lower surface, all combined substantially as described.

In testimony whereof I affix my signature in presence of two witnesses:

JOHN HEANEY.
